UNITED STATES PATENT OFFICE

ZOLTÁN DE NÉMETH, OF NEW YORK, N. Y.

SAFETY DEVICE FOR PORTABLE OIL BURNERS

Application filed August 27, 1930. Serial No. 478,480.

This invention relates to improvements in portable heaters, lamps and like apparatus in which kerosene or other fluid fuels are consumed in producing a flame and in which a tubular wick is used, this application being for similar subject matter as that disclosed in my abandoned application filed Oct. 10th, 1924, Serial Number 742,803.

Such devices are easily subject to accidental upsetting, creating a dangerous fire hazard which, because of the highly combustible nature of the liquid fuel used, is liable to cause a conflagration to ensue.

It is therefore an object of the present invention to provide means for eliminating such danger by the provision of a device which will automatically and instantaneously extinguish the wick flame, should the normal vertical position of the burner become changed to other than an upright position within certain prescribed limits.

This object is attained by the novel construction and arrangement of parts herein-after described and illustrated in the accompanying drawings, forming a material part of this disclosure, and in which:—

Figure 1 is a longitudinal sectional view of a burner including one form of the invention in normal operative position.

Figure 2 is a similar but partial view of a like burner showing the device in its raised position.

Figure 3 is a transverse sectional view taken on line 3—3 of Figure 1.

In the drawings the numeral 10 designates in general the upper element of a container for the liquid fuel for which it serves as a cover.

As shown, the cover element 10 may be dome-shaped and provided with an annular raised offset 11, having an inreaching flange 12, which may be continued upward in the form of a cylindrical wick barrel 13.

Supported in the container is a tubular sleeve 14, its upper edge extending coincidently with the top of the wick barrel 13, while therebetween is a wick 15, this tubular wick being moved up and down by means ordinarily employed.

The burner element 16, shown in broken

lines, carries at its lower edge a level ring 17, having at its inner edge a downreaching flange 18, and at its outer edge is a spreader 19 turned at its upper edge downwardly to constitute a skirt 20, these flame spreader elements are normally held in position by a downreaching annulus 21, secured in any preferred manner by the inner tube 14, the wick 15 being adapted, when in its highest raised position, to contact with the under side of the ring 17, thus the upper edge of the tubular wick is exposed when in a raised position, and due to the capillary attraction of the wick the fuel is raised so that upon the application of a flame, the upper end of the wick will become ignited and the flame spread outwardly, due to the elements 19 and 20.

Mounted on the flange 12 is an annular flange 23, having at its outer edge a raised cylindrical casing 24, offset inwardly as at 25, and then having an upwardly projecting member 26 terminating in an annular bevel 27.

A pair of opposed pivots 30 are mounted in the element 24, near its upper offset portion, and pivoted thereon are levers 31 having weights 32 at their outer extremities, these levers extending through openings 33 in the casing 24, while their opposite inner ends 34 are adapted to normally engage in the manner of detents with a catch ring 35 formed with or secured to the tube 13.

Positioned on the flange 23, on the opposite sides of the device, are the central portions 36 of bent round springs 37, terminating in eyes 38, which are secured to the inner surface of the casing 24, these springs being so positioned as to raise the extinguisher and cause its bevelled surface 27 to make intimate contact with the inner surface of the spreader skirt 20, thereby closing off oxygen necessary to combustion of the wick 15.

Normally the weights 32 act to maintain the extinguisher in its lowered position, but allowing it to freely operate when the weights are moved by gravity outwardly to free the catches 34 from the ring 35, and in order to prevent the device from mischievous han-

dling an arcuate guard 39 is provided to seat on the collar 19 at its offset portion 11.

In the modification indicated in Figure 2 the wick tube elements 13' and 14', together with the wick 15', remain as previously described, but the catch ring 35 is removed from the wick tube 13. A corresponding catch ring 35' is formed on a sleeve 40, having an outturned flange 41 resting on the cover plate flange 12'.

Engageable with the hook ring 35' are hooks 34' formed on levers 31', actuated by the weights 32', the lever being pivoted at 30' on pins passing through a portion of a cylindrical extinguisher 42, which has a flange 43 normally engaged on the corresponding flange 41, while at the upper edge of the extinguisher is an upright element 44 having a bevelled annular surface 45, which, when raised, is adapted to make close contact with the inner surface of the flame spreader 20'.

In this type there are mounted on the flange 41 spring bases 36', having raised elements 37' terminating in eyes 38', which engage the extinguisher sleeve 42 normally exerting sufficient pressure to maintain latching contact between the elements 34' and 35', thereby retaining the extinguisher in its normal lowered position, but which is raised by the effect 30 of the springs when the levers 31', are moved out of their normal position, as by tilting of the burner, in a manner which will be clearly understood.

When the burner is in use the extinguisher tube 42 is pushed down as far as it will go, and held by its own weight, combined with the weight of the levers checking the upward thrust of the springs 36', in which position the wick 15' will burn freely.

However, upon tilting the apparatus, the weights become displaced from the catch ring allowing the levers carrying them to move under the action of the springs, to operate the extinguisher tube, raising it so as to 45 cover the entire outer surface of the wick barrel and contact with the flame spreader, thus completely closing off the air necessary to support combustion of the wick and instantly extinguish the flame.

While certain preferred embodiments of this device have been shown and described, it will be understood that changes in the form, arrangements, proportions, sizes and details thereof may be made without departing from the scope of the invention as defined in the appended claims.

Having thus described the invention, what is claimed as new and desired to secure by Letters Patent, is:—

1. A portable oil burner comprising an upright wick-barrel, a flame spreader exceeding the diameter of said barrel disposed spacedly thereabove, a flame extinguisher having an expanded lower portion constituting a casing slidable on said barrel to con-

tact said spreader closing the opening therebetween, a circumjacent catch ring on said barrel, a plurality of weighted radial levers pivoted in said casing to control the movement thereof by contact with said catch ring, 70 said levers becoming displaced upon tilting the burner from an upright position and resilient means to raise said casing upon release of said levers from said catch ring.

2. A safety device for portable oil burners 75 comprising in combination with a burner having an annular wick barrel composed of spaced tubes, a wick operable therebetween and a flame spreader, of a sleeve adjustably carried by said wick barrel, a bevelled flange on said sleeve extending outwardly, a hollow casing slidable on the outer of said barrel tubes, opposed weight carrying levers pivoted on said casing, said levers having in-reaching detents, a circumjacent catch ring 85 on said sleeve to engage said detents, springs to exert an upward pressure on said casing, a bevelled top on said casing to make close contact with said flame spreader upon tilting of the burner thereby causing said weighted 90 levers to release the detents from said catch ring and an annular guard spaced circumjacent said weights.

3. A safety device for portable liquid fuel burners, comprising a tubular sleeve encircling the burner wick, a flame spreader having a conical skirt, a hollow annular casing slidable on said sleeve, a plurality of levers pivoted in said casing to extend radially outward, said levers having in-reaching detents, 100 resilient means for urging said casing upwardly, said casing having a part to close against said skirt, means normally engaging the detents of said levers whereby the casing is held retracted while the burner is upright, 105 and a concave guard spaced circumjacent said casing and levers.

In testimony whereof I affix my signature.

ZOLTÁN DE NÉMETH.
